(57) **CLAIM**

The ornamental design for an exercise machine as shown and described.

DESCRIPTION

FIG. 1 is a top, front, left perspective view of an exercise machine showing our new design;

FIG. 2 is a bottom, rear, right perspective view thereof;

FIG. 3 is a top, rear, right perspective view thereof;

FIG. 4 is a top, rear, left perspective view thereof;

FIG. 5 is a front view thereof;

FIG. 6 is a rear view thereof;

FIG. 7 is a right side view thereof;

FIG. 8 is a left side view thereof; and,

FIG. 9 is a top view thereof.

The broken lines depicting the remainder of the exercise machine form no part of the claimed design.

1 Claim, 9 Drawing Sheets
